UNITED STATES PATENT OFFICE.

WILLIAM KAYLOR, OF MUSKOGEE, OKLAHOMA, ASSIGNOR OF ONE-FOURTH TO J. H. WOODCOCK, ONE-EIGHTH TO J. T. ROBERTS, AND ONE-EIGHTH TO M. K. THOMPSON, AND ONE-EIGHTH TO O. A. WELLS AND ONE-SIXTEENTH TO WILLIAM T. HUTCHINGS, BOTH OF MUSKOGEE, OKLAHOMA.

WRENCH.

1,118,018.

Specification of Letters Patent.

Patented Nov. 24, 1914.

Application filed March 26, 1914. Serial No. 827,396.

To all whom it may concern:

Be it known that I, WILLIAM KAYLOR, a citizen of the United States, residing at Muskogee, in the county of Muskogee and State 5 of Oklahoma, have invented certain new and useful Improvements in Wrenches; and I do declare the following to be a full, clear, and exact description of the invention, such as will enable others skilled in the art to 10 which it appertains to make and use the same.

This invention relates to new and useful improvements in wrenches and more particularly to a clamp wrench for railway use, 15 and the primary object of the invention is to provide a wrench of this character in which a stationary and pivoted jaw are provided, whereby a nut may be quickly and readily engaged thereby, the pivoted jaw 20 operating automatically.

A further object of the invention resides in providing a wrench in which the pivoted jaw thereof is provided with shoulders, one being designed to form an engaging shoulder 25 for the object, and the other a stop shoulder for engagement with a portion of the head of the wrench.

Still another object of the invention resides in providing a device which is simple 30 and durable in construction, inexpensive to manufacture, and one which will be very efficient and useful in operation.

With these and other objects in view, my invention consists in the novel features of 35 construction and combination and arrangement of parts, as will be hereinafter referred to and more particularly pointed out in the specification and claims.

In the accompanying drawings forming 40 part of this application: Figure 1 is a plan view of a wrench constructed in accordance with my invention; Fig. 2 is a longitudinal section therethrough; Fig. 3 is an edge elevation of the device; and Fig. 4 is a transverse section therethrough as seen on line 45 4—4 of Fig. 2.

In describing the invention, I shall refer to the drawing in which similar reference characters designate corresponding parts 50 throughout the several views and in which—

1 indicates a shank of any desired length on one end of which is formed a head 2, the latter being somewhat arcuate in design, and

formed on one end of this head to project longitudinally thereof is a jaw 3 forming 55 the stationary jaw of the wrench. The stationary jaw has the engaging face thereof arranged substantially at right angles to the outer face of the head member 2 and said head member 2 is slotted at the end thereof 60 opposite that on which the jaw 3 is formed, said slot being indicated as at 4. Pivoted on a pivot pin or pintle 5 extending through the walls of this slotted portion 4 is a pivoted jaw 6, the latter being designed for co- 65 operation with the stationary jaw 3.

In order to provide a neat appearing and perfect operating jaw, the same is reduced on its inner end to form a tongue 7, the latter being received in the slotted portion 4 70 of the head member, and this tongue or reduced portion 7 of the jaw 6 is somewhat arcuately designed. A shoulder 8 is formed on the tongue portion 7 which is arranged substantially at right angles to the outer engaging portion of the jaw and this shoulder 8 completes the formation of the outer face of the head 2 when said jaw 6 is disposed in its normal position as shown in full lines in Fig. 1 of the drawing. When the jaw 6 80 is disposed outwardly, however, with respect to the stationary jaw 3, this shoulder projects outwardly in the space between the jaws and is adapted for engagement with the object to be grasped. In order to limit 85 the outward swinging movement of the jaw 6 with respect to the stationary jaw 3, an additional shoulder 9 is formed on the tongue portion 7 which is designed to abut a shoulder 10 formed on the inner wall of 90 the slotted portion 4. It will be understood that in the actuation of the wrench, the shoulder 8 on the pivoted jaw 6 binds against the nut or other object engaged between the jaws, but when drawing back on the wrench for another hold on the nut, this jaw 6 is adapted to move outwardly, so that the shoulder 9 limits this outward movement of the jaw by abutting the shoulder 10 on the head of the wrench.

As stated above, the 100 tongue portion 7 of this pivoted jaw 6 is pivotally held between the walls of the slotted portion 4 of the head by means of a pin or pintle 5 and this pintle is of screw-like formation, the same being provided 105 with a slot in one end and threaded at the

other for engagement with threads in the opening of one wall of the slotted portion. Thus, it will be seen that this pintle may be readily applied or removed when desired, 5 so that in case of necessity, the movable jaw 6 may be readily removed from the head of the wrench.

From the foregoing description of the 10 construction of my improved wrench, the manner of applying the same to use and the operation thereof will be readily understood, and it will be seen that I have provided a device which is simple and durable in construction, inexpensive to manufacture, and 15 one which will be very efficient and useful in operation.

While I have particularly described the 20 elements best adapted to perform the functions set forth, it is obvious that various changes in form, proportion, and in the minor details of construction may be resorted to without departing from the spirit or sacrificing any of the principles of the invention.

Having thus described my invention, what 25 I claim is:

1. A wrench of the class described comprising a shank, a head formed on one end thereof provided with a flat outer face, a 30 fixed jaw formed on one end of head and having its engaging face arranged at right angles to the flat face thereof, the opposite end of said head being slotted, a movable jaw provided with a reduced segmental inner end pivotally held between the walls of the slotted portion of said head, shoulders formed in the peripheral edge of the segmental portion of the movable jaw and arranged contiguous with and at right angles 35 to the engaging face thereof, to provide a gripping portion thereon, and means also formed on the segmental portion of said movable jaw adapted for engagement with a portion of the head on said shank to limit 40 the outward swinging movement of said movable jaw on the head.

2. A wrench of the class described comprising a shank, a head formed at one end thereof provided with a flat outer face

slotted at one end of the same, a fixed jaw 50 formed on the opposite end of said head and having its engaging face extending substantially at right angles to the flat face of said head, a movable jaw provided with a reduced arcuate portion pivoted between the 55 walls of the slotted portion of said head, the peripheral edge of said arcuate portion, inwardly of the pivotal point being provided with a pair of spaced shoulders, one of said shoulders being designed to form a gripping portion on the movable jaw, and an additional shoulder formed on the inner wall of the slotted portion of said head adapted to abut the other shoulder on said arcuate portion to limit the outward swinging movement of said movable jaw on the head.

3. A wrench of the class described comprising a shank, a head formed on one end thereof provided with a flat outer face, a 70 fixed jaw formed on one end of said head and having its engaging face arranged at right angles to the flat face of said head, the opposite end of said head being slotted, a movable jaw provided with a reduced segmental inner end pivotally held between the walls of the slotted portion of said head, shoulders formed in the peripheral edge of the segmental portion of the jaw and arranged in planes substantially at right 75 angles to one another, the one shoulder being arranged contiguous with and at right angles to the engaging face of the movable jaw to provide a gripping portion thereon, and an additional shoulder formed on the 80 inner wall of the slotted portion of the head adapted to abut the other shoulder on the segmental portion to limit the outward swinging movement of the movable jaw on 85 said head.

In testimony whereof I have hereunto set my hand in presence of two subscribing witnesses.

WILLIAM KAYLOR.
